UNITED STATES PATENT OFFICE.

PERLEY R. GLASS, OF QUINCY, MASSACHUSETTS, ASSIGNOR TO PEERLESS MACHINERY COMPANY, OF BOSTON, MASSACHUSETTS, A CORPORATION OF MASSACHUSETTS.

EYELETING-MACHINE.

SPECIFICATION forming part of Letters Patent No. 701,263, dated May 27, 1902.

Application filed October 30, 1901. Serial No. 80,475. (No model.)

To all whom it may concern:

Be it known that I, PERLEY R. GLASS, of Quincy, county of Norfolk, and State of Massachusetts, have invented an Improvement in 5 Eyeletting-Machines, of which the following description, in connection with the accompanying drawings, is a specification, like letters on the drawings representing like parts.

The present invention relates to an eyeletting-machine of that class in which the material is perforated by coöperating members, such as a punch and anvil, one of said members being laterally movable, while the eyelets are clenched by a setting member which is moved toward the perforation when the laterally-movable member is out of the way.

The machine embodying the invention is provided in addition to the punching members with upper and lower setting-dies, the former being arranged to be moved into position over the punched opening or perforation and the latter being arranged to pick up an eyelet and clench the same in the perforation in conjunction with the former when one of 25 the punching members has been laterally moved to permit the setting-die to coöperate. In accordance with the present invention the upper setting-die has a rigid support to sustain the thrust of the lower setting-die, the 30 parts being provided with mechanism whereby the upper setting-die is moved into position over the punched opening after the punch has left the said opening in its upward longitudinal movement, but prior to the movement of the coöperating die to present and 35 clench the eyelet. As herein shown, the longitudinal movement of the punch is utilized to move the setting-die into and out of position, the said setting-die normally standing 40 in line with the punch, but being arranged to be moved out of alinement therewith as the punch descends and into alinement therewith as the punch rises. This may be advantageously accomplished by pivotally connecting the said setting-die with its support 45 and also connecting the same, as by a link, with the punch or punch-rod, so that the longitudinal movement of the punch will be transmitted to the setting-die to produce a 50 swinging or pivotal movement thereof to carry

the same out of alinement with the punch during the punching operation and into alinement with the perforation previously made by the punch during the setting operation. By this construction the setting-die is positively moved in both directions and a rigid support for the said setting-die is afforded independently of the punch-rod to receive the thrust in the clenching operation.

Figure 1 is a partial front view of a machine embodying the invention; and Figs. 2, 3, and 4 are details, on a larger scale, showing the punch and upper setting device in different positions to illustrate the operation.

The invention is shown as embodied in a machine of the kind described in a prior patent, No. 636,035, granted to me October 31, 1899, the principal operative parts of which need not, therefore, be described in detail, as they may be understood by reference to the said prior patent. In this type of machine the punch is laterally movable to feed the material, and the invention will be hereinafter described as applied to such a machine, with the understanding, however, that the mechanism of the invention may be equally well applied to machines of other kinds.

The parts of the machine which enter into the present invention are the punch-rod *a*, which is provided with the punch proper, *a*², the said punch-rod having a longitudinal reciprocating movement in a head *b*, which is shown as arranged to travel laterally in order to provide for the lateral feed and return movements of the punch. As herein shown, the mechanism for producing these movements is the same as that shown and described in the prior patent above referred to and will therefore not be further described herein. In conjunction with these parts the machine is provided with a reciprocating lower set *c*, provided with a feed-finger *c*², which will pick up and present an eyelet in the ordinary way, the said lower setting device coöperating in the clenching operation with an upper setting-die *d*, the construction and operation of which embody the main features of the present invention. In accordance with the invention the said upper set- 100

ting-die d has a rigid support, so as properly to receive and resist the upward thrust of the lower setting-die c in the setting operation regardless of the position of the punch-rod, the said die d being shown as formed at the end of an arm or support d^2 , pivotally connected at d^3 with a portion of the traveling head b , which produces the lateral movement of the punch-rod. As herein shown, 5 Fig. 1, the setting-die d normally stands in alinement with the punch-rod a , but is arranged to be positively moved out of the way during the downward or punching movements of the said rod, as shown in Fig. 2, 10 where the punch is illustrated as having descended to perforate the material. This movement may advantageously be obtained by connecting the arm d^2 with the punch-rod a by means of a link d^4 , the pivotal support 15 of the arm d^2 not having any longitudinal movement, so that the downward movement of the punch-rod a through the agency of the link d^4 will swing the arm d^2 to one side, so that the punch a^2 can descend into contact 20 with the surface of the material. At the end of the punching operation (illustrated in Fig. 2) the punch rises slightly, as described in my prior patent above referred to, so as to be released from contact with the support 25 or anvil without, however, becoming disengaged from the material, the lateral feed movement then taking place, so that the parts are brought to the position shown in Fig. 3, in which the punch and the punched opening 30 stand directly over the lower set c . The punch then rises from the material, which at this period is held in position by means of the presser-foot e , and in rising causes the arm d^2 to be swung on its pivot d^3 until the 35 upper set d comes into alinement with the punch-rod directly over the punched opening, as shown in Fig. 4. The lower set c then rises, the presser-foot e at the same time being lifted from the surface of the material to 40 release the same, and the eyelet is clenched between the sets, as shown. The upper set is arranged to stand slightly above the surface of the material, so that an eyelet will be 45 readily disengaged therefrom after it has been clenched, the presser-foot e descending prior to the return lateral movement of the punch, the upper set therefore being readily disengaged from the material during such return movement. In the next downward movement 50 of the punch the upper setting-die d is swung out of the way, so as not to interfere with the punching operation, and the operations are repeated, as above described. By the construction shown it will be seen that 55 the setting-die d has a positive rigid support independent of the punch a^2 and a positive movement in both directions, so that it cannot fail to be properly positioned while the punch-rod a is relieved of the pressure during 60 the setting operation.

The link d^4 is shown as directly connected to a collar d^5 or equivalent adjusting device

on the punch-rod a , the said collar being clamped to the punch-rod after being moved to the proper position to bring the setting-die 70 directly over the perforation in the material prior to the setting operation. This construction or its equivalent constitutes adjusting means for the setting-die.

While the construction chosen as an illustration of the invention and herein shown is believed to be simple and practicable, it is not intended to limit the invention to such specific construction and arrangement, since modifications may obviously be made without departing from the invention.

I claim—

1. In an eyeleting-machine, the combination with a punch having a longitudinal movement to punch the material; of a setting-die 85 connected with a rigid support to thereby sustain the thrust; means for laterally moving said setting-die into and out of alinement with the longitudinal axis of said punch; and a coöperating setting-die, as set forth. 90

2. In an eyeleting-machine, the combination with a punch; of means for reciprocating said punch to perforate the material; a setting-die having a pivotal support which does not partake of the reciprocating movement of the punch; means for connecting the said punch with said setting-die whereby the latter is swung into and out of alinement with the punch in response to the reciprocating movement thereof; and a coöperating setting-die, as set forth. 100

3. In an eyeleting-machine, the combination with a punch having a reciprocating movement; of a laterally-movable carrier for said punch; a setting-die having a pivotal 105 connection with said carrier; means for swinging said die on said pivot into and out of alinement with said punch; and a coöperating setting-die, as set forth.

4. In an eyeleting-machine, a reciprocating 110 punch; a setting-die having a support stationary with relation to the punch; adjustable means for connecting said die with said punch; and a coöperating setting-die, as set forth. 115

5. In an eyeleting-machine, a reciprocating punch; a setting-die having a pivotal support; a link connecting said punch with said die; and a coöperating setting-die, as set forth. 120

6. In an eyeleting-machine, a punch having a reciprocating movement; a laterally-movable carrier for said punch; a setting-die having a pivotal connection with said carrier; a link connecting said punch with said die; 125 and a coöperating setting-die, as set forth.

In testimony whereof I have signed my name to this specification in the presence of two subscribing witnesses.
